UNITED STATES PATENT OFFICE.

JOHN EDWARD THORNTON, OF ROCHESTER, NEW YORK, ASSIGNEE TO JOHN OWDEN
O'BRIEN, OF MANCHESTER, ENGLAND.

APPARATUS FOR PRODUCING POSITIVES FOR NATURAL-COLOR CINEMATOGRAPHY.

1,169,098.

Specification of Letters Patent. Patented Jan. 18, 1916.

Application filed May 9, 1913. Serial No. 766,597.

To all whom it may concern:

Be it known that I, JOHN EDWARD THORNTON, a British subject, residing at Rochester, New York, United States of America, have 5 invented certain new and useful Improvements in Apparatus for Producing Positives for Natural-Color Cinematography, of which the following is a specification.

This invention relates to one of the steps 10 in producing a complete color picture single width film for cinematograph or motion pictures by superimposing two or more section color films such as described in my former application Serial No. 733633.

15 Taking for example a three color film it is produced by printing three series of section color pictures side by side on a triple width film and developing and coloring same as described in my concurrent application 20 Serial No. 766,595.

The object of this invention is to provide apparatus whereby such a film, (or a triple width film produced by any other means or method) can be slit into three sectional parts 25 and these sectional parts superimposed and cemented together to form a single width complete color film.

It comprises apparatus for drawing the film forward, slitting it, damping it, or applying 30 an adhesive to it, bringing the sections together one over the other in correct register and causing them to unite and finally drying the film in its finished state.

The invention will be fully described with 35 reference to the accompanying drawings.

Figure 1 is a perspective view of a piece of triple width film with three series of section color pictures thereon. Fig. 2 is a sectional diagrammatic view of apparatus for 40 slitting the film into three and superimposing and uniting the three sections. Fig. 3 is a plan of same. Fig. 4 is a perspective view of pieces of the three sections of the film as they are being superimposed and united.

45 The apparatus is constructed with a suction feed box B by which the triple width film A is fed to the machine, a series of cutting rotary disks or knives C by which the film is slit into three sections a' a² a³. 50 a second suction feed box B' by which the slit film is carried forward from the cutting knives, a chest or chamber D for steam or vapor with guide rollers d and d' and an inlet pipe d² for steam or moistened air, 55 into which the film which has been previ-

ously cemented and dried is passed for the purpose of damping it. The damping chest or chamber is provided with an outlet aperture d⁴ for the film and above the chest one or more pairs of reciprocating pins E or 60 hooks or similar devices are mounted to engage the perforations in the three film sections and raise them into accurate registration before being united together. Adjacent to the reciprocating lifting pins E dabbing pads or brushes F and F' acting against a table and rollers G are placed to firmly compress and unite the three superimposed film color sections a' a² a³ into a single width complete color picture film. Instead 70 of damping a previously cemented film the adhesive material may be applied to the film by the rollers d'. The suction feed boxes B B' are of known construction with an endless band b of silk ribbon felt perforated 75 metal or canvas wire gauze or other suitable material traveling over a suction box b' with perforated top in which a partial vacuum is formed by a fan or pump (not shown). A single band b passing over 80 guide pulleys may travel over both suction boxes B B' being carried on guide rollers below the cutting disks C. The lifting and registering pins E are operated by eccentrics e or in any other well known manner such 85 as employed in the feed of film perforating machines.

In operation the triple width perforated film A is fed into the machine from a reel or other receptacle by the suction box B and 90 slit into three sections a' a² a³ by the cutting disks C. From the cutting disks the severed film is fed by the section box B' into the chest or chamber D over the guide rollers d from which it falls in loops or festoons 95 and is therein damped if previously cemented and dried or it has an adhesive applied to it by the rollers d'.

The three film sections a' a² a³ are kept 100 separate and out of contact by the rollers or bars d' and as they pass out of the chest through the aperture d⁴ are brought into line one over the other. In a damp or sticky condition the three film sections a' a² a³ 105 emerge from the chest D in a vertical direction and are engaged through their perforations by the lifting and regulating pins or hooks E and as the weight of the films rests upon the pins the section color pictures 110 on each are brought into correct register

one over the other and they are thus assembled in their relative positions superimposed. In this position the dabbing pads or brushes F and rollers G press them into absolute contact and unite them into a complete film after which the strip passes forward over the rollers H and H' into a drying chamber K. The drying apparatus is a chamber with rollers K over which the film travels spirally and is fed with warm filtered air by a fan. The finished film is then wound upon a reel in any ordinary way.

Although described as applied to a three color film the apparatus may be adapted for a two-color film or for a film with more than three colors.

It will be understood that a machine such as described requires the highest class of workmanship, careful construction, and accuracy in all details, especially when it is understood that an error of as small as one-thousandth part of an inch in the superimposing, assembling and uniting of the several sections or layers of every picture is sufficient to render the entire film useless.

What I claim as my invention and desire to protect by Letters Patent is:—

1. Apparatus for producing single-width complete color picture films for cinematograph or motion pictures from two or more superimposed color sections comprising in its construction cutters by which the film is slit into two or more sections, means by

which the several sections are superimposed, and registering appliances whereby the pictures are brought into correct register before the sections are secured together substantially as described.

2. In apparatus for producing single-width complete color picture films for cinematograph or motion pictures from two or more superimposed color sections, the combination of reciprocating apparatus arranged to enter perforations in all the sections and operative to advance such sections simultaneously in correct register, and means for pressing the registered sections into contact.

3. In apparatus for producing single-width complete color picture films for cinematograph or motion pictures from two or

more superimposed color sections, the combination of reciprocating pins arranged to enter perforations in all the sections and operative to advance them simultaneously in correct register, and dabbers for pressing the several registered sections into contact.

4. In apparatus for producing single-width complete color picture films for cinematograph or motion pictures from two or more superimposed color sections, the combination with means for feeding the film forward, of cutters to slit the film into two or more sections, guides to prevent the tacky surfaces of the several sections of film coming into contact before they are accurately registered, registering pins by which the sections are fed forward and dabbers to press the several sections into contact substantially as described.

5. Apparatus for producing a single width complete color picture film for cinematograph or motion pictures from a multi-width film with two or more series of section color pictures comprising in its construction suction feed boxes to feed forward the film, cutters to slit the film into several sections, means for rendering the film adhesive, apparatus for placing the film sections in correct register one upon another and moving the film sections forward, and apparatus to squeeze and unite the film sections.

6. Apparatus for producing a single width complete color picture film for cinematograph or motion pictures from a multi-width film with two or more series of section color pictures comprising in its construction suction feed boxes to feed forward the film, cutting disks to slit the film into several sections, a damping chamber to render the surface of the film tacky, lifting and registering pins to engage the several film sections and place them in correct register one upon another and dabbers to squeeze and unite the film sections.

In testimony whereof I have hereunto set my hand in presence of two subscribing witnesses.

JOHN EDWARD THORNTON.
